Inventor
Samuel D. Leiboff

By his Attorney John Spindler

UNITED STATES PATENT OFFICE.

SAMUEL L. LEIBOFF, OF NEW YORK, N. Y.

APPARATUS FOR EXTRACTING CHOLESTEROL FROM BLOOD.

Application filed September 25, 1924. Serial No. 739,964.

This invention relates to an improved process and apparatus for extracting cholesterol from blood for determining the quantity of cholesterol therein.

5 Among the objects of the invention is the provision of a process of the character and for the purpose described which is comparatively simple, and which may be easily and quickly carried out and gives highly accurate results, and the provision of improved 10 apparatus for carrying out said process which shall be simple and compact in construction, comprised of few and simple parts, easily manipulated, comparatively inexpensive to manufacture, and efficient in operation to a 15 high degree.

Other objects of this invention will in part be obvious and in part hereinafter pointed out.

20 The invention accordingly consists in the features of construction, combinations of elements and arrangement of parts which will be exemplified in the construction hereinafter described and of which the scope of 25 application will be indicated in the following claims.

In the accompanying drawing, in which is shown one of the various possible illustrative embodiments of this invention,

30 Fig. 1 is a perspective view showing a multiple condenser and an extraction tube connected thereto used in carrying out the process embodying the invention;

Fig. 2 is a perspective view of the extraction tube; and

35 Fig. 3 is a front elevational view (partly in section) of the apparatus arranged to carry out the process.

The process in a general way consists in 40 applying the blood sample to a piece of fat-free absorbent material then extracting cholesterol from the said sample by a suitable agent through the said material. The process is preferably carried out by means of 45 the apparatus now to be described.

Referring in detail to the drawing, 10 denotes a multiple condenser comprising a body portion or jacket 11 made of any suitable material, but preferably of copper or the like, said jacket 11 having outwardly ex-

tending in opposite directions adjacent the lower and upper ends thereof inlet 11^a and outlet 11^b, respectively, for the purpose hereinafter to appear.

For closing the ends of the jacket 11, two 55 similarly constructed members 12 and 13 shaped to correspond to the end openings of the jacket 11 may be provided and are preferably made of rubber or the like suitable material that will form a water tight joint 60 with the wall of jacket 11 when inserted in the said end openings thereof. One or more condenser tubes 14 may be supported in spaced relation within the jacket 11 between the members 12 and 13 which are perforated 65 to permit the end portions 14^a of each tube 14 to extend through and beyond said members 12 and 13, as shown in Fig. 1. Tubes 14 may be made of any suitable material, as for example glass, and the mid-section 14^b of each 70 tube 14 extending within the jacket 11 is preferably substantially greater in cross-section than the end portion 14^a so as to provide a relatively large cooling surface. With the condenser 10 constructed as described above, 75 it is apparent that a broken tube 14 may be easily replaced by simply removing either of the members 12 or 13.

15 indicates in general an extraction tube which may be made of glass or a like suitable 80 material and is formed to have a bulb shaped end 15^a, a contracted mid-portion 15^b which provides an interior annular shoulder 15^c between it and an upper or neck portion 15^d. The mid-portion 15^b may have a marking 17 85 thereon to serve as a graduate measure and is here shown to designate 5 cubic centimeters (5 c. c.). The shoulder 15^c provides a support for a dished disc of filter paper 16.

To connect the extraction tube 15 to the 90 condenser 11, a perforated cork stopper 18 or the like suitable closure may be provided, the stopper 18 being constructed to make a tight connection between the neck 15^d of the tube 15 and one of the lower end portions 95 14^a of the condenser 10.

The process and the carrying out of the same by means of the apparatus will now be more fully described.

A measured amount of chloroform is pu⁺ 100

into the extractor tube 15, as for example 5 c. c. up to the mark 17. A disc of heavy, fat-free filter paper 16 is dropped into the tube 15 so as to rest on the shoulder 15^c and 5 a measured quantity, for example (0.25 c. c.) of oxalated blood is pipetted on to the filter paper 16 which immediately absorbs the same.

The stopper 18 is inserted into the neck 10 15^d and the tube 15 attached to the lower end of a condenser tube 14. A number of blood samples may be tested in one operation by similarly preparing a corresponding number of tubes 15 and attaching them to the 15 condenser tubes 14. The bulb ends 15^a of all the tubes 15 are immersed in a beaker 19 of hot or boiling water, placed over a suitable heating source such as a small electric heater 20, the water in the beaker being kept above 20 the level of the chloroform in the tube as shown in Fig. 3.

The inlet 11^b of the condenser 11 is then connected by means of a rubber tubing 21 with a cold water supply (not shown) and 25 water is kept continuously circulating through condenser 11 and discharging from the outlet 11^a through a tubing 22.

The extraction which takes place during the boiling of the chloroform is completed 30 after thirty minutes, during which time the distilling chloroform vapor passes up the tube 15 through a small central opening 16^a provided in the filter paper disc 16 and into the condenser tube 14 where the vapors are 35 cooled and condensed. The liquefied chloroform drips back on the filter paper disc 16 in the tube 15 and in passing through the filter paper extracts the cholesterol from the absorbed blood sample.

40 After the extraction operation is completed, the tube 15 is removed and placed in a beaker of cold water. Cool chloroform is then added exactly to the mark 17, and the green color is then developed in the usual 45 manner by adding acetic anhydride and sulphuric acid and leaving the solution in a dark place for a short time.

The cholesterol in the sample is then determined in the usual manner by comparison 50 with a known standard.

It has been found that this method, as carried out with the apparatus described, not only yields comparatively more accurate results but consumes a minimum of time, requiring, from actual experience, less than 55 an hour for a complete test. With this apparatus, furthermore, a number of samples may be tested simultaneously in a most convenient manner, since the whole assembly 60 occupies little space, and the parts thereof are easily manipulated.

With other methods and apparatus heretofore used, it has been furthermore necessary to employ comparatively large blood

samples while with the method and apparatus above described a small blood quantity, as for example 0.25 c. c. has been found to give highly satisfactory results.

It will thus be seen that there are provided a process and apparatus in which the several objects of this invention are achieved and which are well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. In a device for determining cholesterol in blood, a tube having a closed end portion 85 adapted to hold an extracting fluid, a contracted mid-portion forming a shoulder for supporting a porous partition over said end portion and means formed on said contracted portion for measuring a desired quantity of 90 the fluid in said end portion.

2. In a device for extracting cholesterol from blood, an extraction tube formed with a closed end adapted to hold an extracting fluid and a contracted mid-portion, said portion 95 forming a shoulder and a porous, absorbent partitioning member supported on said shoulder adapted to receive thereon a blood sample for exposing same to the action of the extraction fluid.

100 3. In a device for extracting cholesterol from blood, an extraction tube formed with a closed end adapted to hold an extracting fluid and a contracted mid-portion, said portion forming a shoulder and a porous, absorbent partitioning member supported on said shoulder adapted to receive thereon a blood sample for exposing same to the action of the extraction fluid, said member having a through opening to permit the passage 110 of the extraction fluid therethrough.

105 4. In a device for extracting cholesterol from blood, an extraction tube formed with a closed end adapted to hold an extracting fluid and a contracted mid-portion, said portion 115 forming a shoulder and a porous, absorbent partitioning member supported on said shoulder adapted to receive thereon a blood sample for exposing same to the action of the extraction fluid, said member having a through opening to permit the passage of the extraction fluid therethrough, and graduate marking on the contracted section 120 for measuring a desired quantity of the fluid in the tube.

125 5. An extracting cup comprising a bulbous portion, a reduced neck portion connected to said bulbous portion and a tubular portion

of a diameter greater than said neck portion, said reduced neck portion and said tubular portion being connected by a shoulder portion, as and for the purpose described.

5 6. An extracting cup comprising a bulbous portion, a graduated reduced neck portion connected to said bulbous portion, and a tu-

bular portion of a diameter greater than said neck portion, said reduced neck portion and said tubular portion being connected by a shoulder portion, as and for the purpose described. 10

In testimony whereof I affix my signature.

SAMUEL L. LEIBOFF.
